W. SCHWARTZ

SKYLIGHT

Filed June 3, 1925

Fig. 1: A technical drawing of a building facade. The facade features a central entrance with a pedimented portico supported by four columns. Above the portico is a horizontal band of windows. The main floor has six large windows, and the upper floor has a row of smaller windows. The roof is a gabled structure with multiple skylights. Various parts of the building are labeled with numbers:

- 18: Left edge of the building.
- 12: Column of the portico.
- 13: Column of the portico.
- 15: Gable end of the roof.
- 14: Gable end of the roof.
- 19: Gable end of the roof.
- 22: Top of the pediment.
- 26: Column of the portico.
- 24: Column of the portico.
- 25: Column of the portico.
- 27: Column of the portico.
- 9: Window on the main floor.
- 4: Window on the main floor.
- 13: Column of the portico.
- 12: Column of the portico.
- 11: Window on the upper floor.
- 9: Window on the upper floor.
- 11: Window on the upper floor.
- 9: Window on the upper floor.
- 11: Window on the upper floor.
- 9: Window on the upper floor.
- 11: Window on the upper floor.
- 8: Window on the upper floor.
- 5: Column of the portico.
- 1: Bottom left corner.
- 23: Bottom left corner.
- 03: Bottom right corner.

INVENTOR
William Schwartz
BY Joseph Karsik
ATTORNEY

UNITED STATES PATENT OFFICE.

WILLIAM SCHWARTZ, OF ST. LOUIS, MISSOURI.

SKYLIGHT.

Application filed June 3, 1925. Serial No. 34,623.

This invention relates to a certain new and useful improvement in skylights. It has for its principal objects the provision of a ventilating skylight which may be controlled and 5 operated, at will, from a position below; to provide for the automatic opening of the skylight when the temperature in the building raises to a certain degree; to produce a simple and compact structure which takes up only a 10 minimum space upon the roof of the building; and to attain certain advantages as will hereinafter more fully appear.

The invention resides in the novel features of form, construction, arrangement, and combination of parts hereinafter described and pointed out with particularity in the appended claims.

In the accompanying drawing, which illustrates a practical adaptation and embodiment 20 of my invention,—

Figure 1 is a view of the complete skylight, partly in end elevation and partly in transverse vertical section;

Figure 2 is an enlarged fragmentary transverse vertical section of the skylight, taken through or about the middle of one of the 25 ventilating openings and the closure therefor; and

Figure 3 is a fragmentary horizontal section 30 at the corner portion of the skylight.

Referring more in detail and by reference characters to the drawings, 1 designates the rectangular base of the skylight, which, as shown, comprises preferably a brick curbing, 35 although it is obvious that this base may be of any other suitable formation and material.

Extending around the outer edge portion of and suitably fixed to curbing 1, is an anchor-member 2, preferably in the form of an 40 angle, as shown. Secured to the anchor-member 2, is the lower horizontal frame-member 3 of the skylight base structure, preferably of angle section, as shown. The frame-member 3 has corner and intermediate uprights or 45 posts 4, preferably angle bars, as shown, secured thereto and to which the respective mullions 5 and 6 are attached.

The corner mullions 5 are in the form of box-like, sheet metal construction, substantially L-shape in cross-section, with rabbeted 50 marginal portions 7, and having outwardly presented flanges at the base of said portions, as best seen in Figure 3, and co-operating with said flanges and portion in the formation of channels or slideways for the respective ver-

tically slidable doors or closures 9 for the ventilating openings to be presently described, are angle-members 8.

The intermediate mullions 6 are also of box-like, sheet metal construction, substantially T-shape in transverse horizontal section, with rabbeted portions 10 and outwardly presented flanges at the base of said portions, as also best seen in Figure 3, with which angle members 11 co-operate to provide opposite slideways for the doors or 65 closures 9.

The respective mullions 5 and 6 extend down for a considerable distance below the upper edge of the curbing 1, as shown, preferably substantially to the bottom of the curbing, the height of which latter is preferably approximately one-half the over-all height of the side walls of the skylight 70 structure.

At the upper ends of the uprights 4, are horizontal angle members 12, on which a fixed top 13 is mounted. This top, as shown, is preferably of the hip-roof type and comprises a plurality of metal frame members 14 on and 75 between which glass panels 15 are suitably secured.

The doors or closures 9, which are 80 slideable vertically on and between the respective mullions 5 and 6, comprise hollow sheet metal boxes having marginal flanges 16 loosely fitting in the guide-slots in the mullions, the doors or closures 9 being preferably provided on their vertical edge-portions with antifriction rollers 17 which bear upon the opposed 85 faces of the mullions.

Extending around the skylight, just below the top 13, is an overhanging eaves molding or water-shed 18 comprising an inclined sheltering portion having a depending substantially vertical flange 19 at its outer edge, and on the lower edge of which latter is an outwardly extending and downwardly inclined lip or deflecting flange 20; and to further make the structure weather-tight, 90 filler plates or liners 21 are inserted between the respective uprights 4 and the mullions 5 and 6.

The upper portion of the structure may be 100 suitably braced, preferably by tie-rods 22, as shown, connecting the upper angle members 12. So, too, the lower end portions of the mullions 5 and 6 may be tied by angle-members 23, which latter, in addition to bracing the mullions, serve as stops for respective 105 110

doors or closures 9 when they are lowered or fall under the pull of gravity.

The doors or closures 9 are held in raised position, and lowered and restored to raised position, at will, by cords, cables or chains 5 fastened to bracket extensions 25 on the inner faces of the doors or closures and passing over pulleys 26 secured to the angle members 12. At a suitable place within the 10 length of each cord 24, is a fusible link 27. By this arrangement, a theatre or other building may be readily ventilated, as it is only necessary to loosen the cords or cables 24 to permit the doors or closures 9 to drop 15 by gravity and thus uncover the openings, the degree to which the openings are uncovered being full or partial and under the control of the operator from the floor or other convenient position in the building below the 20 skylight. In case of fire or heating of the building above a certain degree, the fusible links 27 will melt and separate the upper portions of the cords or cables 24, whereupon the doors or closures will drop automatically by 25 gravity.

It is thus obvious that a structure is produced which meets with the requirements of fire department and insurance regulations, and, doors or closures 9 being vertically 30 slideable, there are no projections or obstructions to interfere with the work of firemen upon the roof when the doors or closures are opened.

I am aware that changes in the form, 35 construction, arrangement, and combination of the several parts of my new skylight may be made and substituted for those herein

shown and described without departing from the nature and principle of my invention.

Having thus described my invention, what 40 I claim and desire to secure by Letters Patent is:

1. In a skylight, a base curbing having an anchor member thereon, a frame comprising a horizontal angle member secured to said 45 anchor member, uprights comprising angle members secured to said horizontal member, a second horizontal angle member secured to the upper end portions of said upright angle members, a fixed top mounted on said second mentioned horizontal angle member, said top comprising a multiplicity of frame members having glass panels secured thereon and therebetween, a series of box-like sheet metal mullions secured to said upright angle 50 members, said mullions having slideways in their opposed sides, a series of box-like sheet metal closures having marginal flanges working in the slideways of said mullions, and cords secured to said closures and being 55 passed over pulleys on said frame and down to a place below the skylight for operating and holding said closures.

2. In a ventilating skylight, a mullion of box-like structure having opposed rabbetted 60 marginal portions and outwardly presented flanges at the base of said portions, and angle-members fixed to the flanges and co-operating with said marginal portions in the formation of closure slide-ways. 70

In testimony whereof, I have signed my name to this specification.

WILLIAM SCHWARTZ.
